(57) **CLAIM**

I claim the ornamental design for a mobile phone, as shown and described.

DESCRIPTION

FIG. 1 is a front elevational view of a mobile phone of the claimed design showing the mobile phone in a closed position.

FIG. 2 is a front view of the mobile phone of FIG. 1 showing the mobile phone in an open position.

FIG. 3 is a rear elevational view of the mobile phone of FIG. 1.

FIG. 4 is a top view of the mobile phone of FIG. 1.

FIG. 5 is a bottom view of the mobile phone of FIG. 1.

FIG. 6 is a right side view of the mobile phone of FIG. 1.

FIG. 7 is another right side view of the mobile phone of FIG. 1 showing the mobile phone in an open position.

FIG. 8 is a left side view of the mobile phone of FIG. 1.

FIG. 9 is another left side view of the mobile phone of FIG. 1 showing the mobile phone in an open position; and,

FIG. 10 is a perspective view of the mobile phone of FIG. 1 showing the mobile phone in an open position.
